UNITED STATES PATENT OFFICE.

EMORY J. CARTER, OF FREMONT, OHIO, ASSIGNOR TO THE SIMPLE ACCOUNT SALES-BOOK COMPANY, OF FREMONT, OHIO, A CORPORATION OF OHIO.

HOLDER FOR MANIFOLD SALES-BOOKS.

1,165,748.

Specification of Letters Patent.

Patented Dec. 28, 1915.

Application filed April 17, 1911. Serial No. 621,448.

To all whom it may concern:

Be it known that I, EMORY J. CARTER, a citizen of the United States, residing at Fremont, in the county of Sandusky and State of Ohio, have invented certain new and useful Improvements in Holders for Manifold Sales-Books; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to a holder for manifold sales-books or sales-pads, and is designed to furnish a neat, durable, compact means for retaining blocks of sales-slips or memoranda in order and in convenient form for ready use.

My invention relates, more particularly, to a holder composed of sheet metal provided with means for engaging and retaining the pad; provided also with means for holding in place a card for memoranda of sales or the like; provided also with means for holding apart the retained undetached duplicates of sales-slips; provided also with means for detachably holding a sheet of carbon paper independently of the pad and in such manner that the carbon sheet may, at will, be readily and conveniently removed and renewed, and provided also with a hinged cover or lid which, when open, forms a convenient writing surface.

I attain the objects here indicated by means of the devices, construction and arrangement of parts hereinafter described, and shown and illustrated in the accompanying drawings, in which,—

Figure 1 is a perspective view of my holder with the lid or cover elevated and with the pad broken away to show the device for detachably securing the carbon sheet in place; Fig. 2, a transverse sectional elevation of the carbon sheet holder in place, and Fig. 3, an end-view of my holder with a pad in place and with the lid slightly elevated.

Corresponding numerals of reference indicate like parts throughout the drawings.

In the drawings, 1 is a flat rectangular metal sheet having one end 2 and one side 3 turned up to form flanges of a height slightly greater than the thickness of the

pad to be held. The remaining side and end are open.

4 is a sheet metal cover hinged at one end to the top of the flanged portion 2. The hinged parts are operatively connected by means of a pintle 5, which is turned at one end, as at 6, and then backwardly, as at 7, and then outwardly, as at 8. The pintle fits in its bearing with a close fit and when the extended finger 8 is pressed against the inner side of the lid the retained undetached duplicates of sales-slips may, by the pressure of the finger, be held together and in place against the lid and out of the way.

The side-margins of the lid 4 are turned inwardly parallel with the plane of the lid, as at 9, to form grooves 10 for the reception of the margins of memorandum-card 11. The margin of the back 1, opposite the flange 3, is turned inwardly, as at 12, to form a groove 13 for the reception of the margin of the card-board back 14 of the pad. The upturned flange 3 is, at top, turned inwardly and downwardly, as at 15, to form a groove for the reception of the upper margin of a strip 16,—of sheet metal or other suitable material,—which is of slightly less width than the height of the flange 3. At its outer end the strip 16 is turned, as at 17, to form a finger-hold by means of which the strip may be drawn from its groove.

18 is a sheet of carbon paper having one of its side-margins folded about the strip 16, so that when the strip is in place the carbon sheet is securely held in place until the strip 16 is removed from its groove. The strip 16, with its accompanying carbon sheet, being in place, the pad-back 14 is slipped into place in groove 13, as above described, and the device is now ready for use in a manner which will be understood without further description. The plate 1, at its free unflanged end, is notched, as indicated in dotted lines at 1^a to furnish a finger-hold to facilitate the slipping of the pad into and out of the holder.

Having described my invention, what I claim and desire to secure by Letters Patent is,—

1. A manifolding device comprising a rectangular sheet metal plate having a flanged member adapted for engagement with the back of a paper pad, means for securing to said sheet metal plate a sheet of manifolding

105

100

110

paper, a lid which forms a cover for such pad and a hinge connecting said plate and lid and including a pintle extended and bent to form a member for holding certain leaves 5 of such pad against the lid.

2. In a manifolding device, a sheet metal plate having at one of its margins a grooved flange, a metal strip detachably engaged with said groove, a carbon sheet engaged 10 with said strip, said sheet metal plate having at its opposite margin a groove, and a pad engaged with said latter groove and in coöperative relation with said carbon sheet.

3. A device of the described character 15 comprising a rectangular sheet metal plate having at one of its margins an upturned grooved flange, having also at its opposite margin an inwardly turned flange forming

a groove, having also at one end an upturned flange, a strip in the groove first mentioned, a carbon sheet engaged with said strip, a pad having the margin of its back engaged with said inwardly turned flange, a lid hinged to said upturned end-flange, said lid having at opposite margins grooves for the 20 reception of a card, and a pintle forming part of said hinge, said pintle being turned 25 backwardly to overlap the inner surface of the lid.

In testimony whereof I affix my signature in presence of two witnesses.

EMORY J. CARTER.
